(57) **CLAIM**

The ornamental design for a motorcycle body, as shown and described.

DESCRIPTION

FIG. 1 is a perspective view from the front and left side of the motorcycle body which is the subject of my new design;
FIG. 2 is a perspective view from the rear and the right side thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof;

FIG. 8 is a right side view of the motorcycle body shown in the environment of a motorcycle; and,

FIG. 9 is a left side view of the motorcycle body shown in the environment of a motorcycle.

The broken lines in FIGS. 8 and 9 illustrate unclaimed structure.
